UNITED STATES PATENT OFFICE.

WILLIAM J. RUSSELL, OF DETROIT, MICHIGAN.

ACID-TANK.

1,315,241.

Specification of Letters Patent.

Patented Sept. 9, 1919.

Application filed December 12, 1918. Serial No. 266,501.

To all whom it may concern:

Be it known that I, WILLIAM J. RUSSELL, citizen of the United States, residing at Detroit, county of Wayne, State of Michigan, have invented a certain new and useful Improvement in Acid-Tanks, and declare the following to be a full, clear, and exact description of the same, such as will enable others skilled in the art to which it pertains to make and use the same, reference being had to the accompanying drawings, which form a part of this specification.

My invention relates to acid tanks, shown in the accompanying drawings and more particularly pointed out in the following specification and claims.

One object of this invention is to provide a strong, substantial tank constructed of wood, with an inner wood lining or tank held in spaced relation to the first named tank by a plurality of dovetailed members respectively engaging the walls of the outer tank and also the walls of the inner tank or wood lining;—the space between said walls being filled by an acid resisting wall of plastic material.

Another object of the invention is to "break" the joints between the members forming the walls of the tanks by strips which bridge the abutting edges and are lodged in recesses formed in the respective members.

Another feature of the construction are bolts which extend transversely through the respective members forming the walls of the tank to secure the several members in abutting relation.

With the foregoing and other objects in view, which will appear as the description proceeds, the invention resides in the combination and arrangement of parts, and in the details of construction hereinafter described and claimed, it being understood that changes may be made in the precise embodiment herein described without departing from the spirit of the invention.

In the drawings accompanying this specification:—

Figure 1 is a plan view of the tank with a portion broken away that it may be more conveniently shown upon the sheet, and with the strip covering the upper edges of the tank removed.

Fig. 2 is a side elevation of the same with a like portion removed.

Fig. 3 is a cross-sectional view of the tank. Referring now to the letters of reference placed upon the drawings:—

A, denotes the tank, in which walls forming the sides, ends, and bottom are constructed of a plurality of abutting wooden strips B, secured together by transverse bolts D, the heads and nuts being preferably countersunk in the walls of the tank and covered with an acid resisting plastic wall E.

F, denotes a plurality of cross members bolted to the walls of the tank, and G, are similar cross members secured to the bottom of the tank.

H, is an inner tank or wood lining located within the tank A, being held in spaced relation to walls of the latter by dovetailed members I, lodged in the respective walls of the inner and outer tanks. J are strips supported in a recess in the abutting edges of the members forming the walls of both the inner and outer tanks, to bridge the joint between their opposing edges.

K, indicates a wall of acid resisting composition lodged in the space provided between the inner and outer walls of the respective tanks.

L, denotes a strip overlapping the edges of the respective walls of the tank and secured thereto.

Having now indicated the several parts entering into the manufacture of the tank its construction will be readily understood.

It will be noted that the walls of the tank at the corners are securely held together through the coördination of the respective dovetailed members I in the side and end walls.

It will also be evident that should the tank spring or develop a leak, the acid resisting composition K, which is of the low melting point (preferably acid proof asphalt) would operate to seal the opening through the walls of the tank.

What I claim is:

1. A device of the character described comprising an outer tank, an inner tank or lining in spaced relation to the outer tank, means engaging the walls of the inner and outer tanks to maintain them in spaced relation, and a wall of low melting acid resisting material lodged between the walls of the inner and outer tanks.

2. A device of the character described comprising an outer tank formed of a plu-

- 5 rality of wooden members bolted together, strips lodged in recesses formed in the edges of said wood members and bridging the joint between said members, a wood lining spaced from the walls of the tanks, dove-
10 tailed members engaging the walls of the tank and the wood lining, and a wall of acid resisting material filling the space between the walls of the tank and the wood lining.
- 15 3. A device of the character described comprising an outer tank formed of a plurality of wood members, a plurality of bolts extending transversely through said members having their heads countersunk in the walls of said tank, an acid resisting composition covering the heads of said bolts in the countersunk portion, an inner wood lining spaced from the wall of the tank, a wall 20 of low melting acid resisting material filling the space between the walls of the tank and the wood lining, and members covering the edges of the inner wood lining, the wall of acid resisting material, and the wall of the outer tank.
- 25 4. A device of the character described.

comprising an outer wooden tank, an inner wooden tank held in spaced relation to the outer tank, and an inter lining or wall between said tanks of low melting acid resisting asphalt.

30 5. A device of the class described comprising a spaced outer and inner tank each formed of a plurality of wooden members, a plurality of bolts extending transversely through the members of the outer tank, strips lodged in recesses formed in the edges of the members of both tanks, dovetailed members engaging the adjacent walls of the inner and outer tanks, a wall 35 of low melting acid resisting material filling the space between the walls of the inner and outer tanks, and a top strip covering the upper edges of the inner and outer tanks and the wall of the acid resisting material therebetween.

40 In testimony whereof, I sign this specification in the presence of two witnesses.

45 WILLIAM J. RUSSELL.
